DESIGN FOR A TEXTILE FABRIC

Robert Francis Allgor, Bergenfield, N. J.

Application November 13, 1940, Serial No. 96,530

Term of patent 3½ years

To all whom it may concern:

Be it known that I, Robert Francis Allgor, a citizen of the United States of America, residing in Bergenfield, county of Bergen, and State of New Jersey, have invented a new, original, and ornamental Design for a Textile Fabric, of which the following is a specification, reference being had to the accompanying drawing, forming part thereof, wherein the figure of the drawing is a plan view of a textile fabric showing my new design.

I claim:

The ornamental design for a textile fabric, substantially as shown.

ROBERT FRANCIS ALLGOR.
